ELECTRIC SWITCH

James C. Hamilton, Lexington, Mass., assignor to
 Photoswitch, Incorporated, Cambridge, Mass.,
 a corporation of Massachusetts

Application December 9, 1943, Serial No. 513,571

5 Claims. (Cl. 200—67)

1

This invention relates to electric switches and more particularly to thermally actuated rapidly operating spring switches.

It is one of the main objects of the present invention to provide mounting expedients for thermally operated switches of the type described and claimed in copending application Serial No. 513,563, filed on December 6, 1943, including a housing permitting convenient and exact assembly of the electrical and mechanical elements, as well as secure operation of such switches, and means permitting, in correlation with such a housing, exact and convenient adjustment of the relative effect of the temperatures upon which depends operation of the switch.

In one of its aspects, the invention contemplates a mounting for a switch of this type which has a base block on which the moving switch parts can first be assembled, and additional blocks carrying fixed switch contacts and also serving as a protective housing; in another aspect, the invention provides a mounting which permits the fastening thereto in cantilever fashion of two actuator strips at accurately predetermined distance; in a further aspect, the invention provides a construction which permits mounting of similarly shaped switch elements in various ways, as with connected or separated, open or enclosed actuator elements; and in still another aspect, the invention provides a pivot connection between two thermally responsive definitely distanced actuators and a snap switch spring, which connection permits convenient and exact adjustment of the effect of these actuators upon the switch spring.

These and other objects, aspects and features will be more fully apparent from the following description of several practical embodiments illustrating the genus of the invention. The description refers to drawings in which

Fig. 1 is a side view, with the front cover block removed, of a switch according to the present invention with communicating heat compartments;

Fig. 2 a section on line 2—2 of Fig. 1;

Fig. 3 a section on line 3—3 of Fig. 1;

Fig. 4 an expanded section on line 3—3 of Fig. 1;

Fig. 5 a fragmentary side view similar to Fig. 1 but with both cover blocks removed;

Fig. 6 a section on line 6—6 of Fig. 1;

Fig. 7 a front view of a second embodiment of the invention with one actuator compartment;

Fig. 8 a side view of a switch according to Fig. 7;

2

Fig. 9 a section on line 9—9 of Fig. 7;

Fig. 10 a section on line 10—10 of Fig. 7;

Fig. 11 a fragmentary side view seen from the right-hand side of Fig. 8 and with the cover plate removed;

Fig. 12 a fragmentary side view similar to Fig. 11, but with the cover plate in place;

Fig. 13 an isometric view of the cover plate shown in Figs. 8, 9 and 12;

Fig. 14 the front view of a third embodiment of the invention with separated actuators;

Fig. 15 a section on line 15—15 of Fig. 14;

Fig. 16 a fragmentary side view of the switch according to Fig. 14, seen from the right-hand side of Fig. 15;

Fig. 17 a perspective view of the insulation sleeve upon which the heater is wound as shown in Fig. 4;

Fig. 18 an isometric representation of the switch spring, indicating various possibilities of juncture with the connector; and

Fig. 19 a vertical detail section through a connector having three adjustment screws.

In the embodiment shown in Figs. 1 to 6, the switch assembly according to the invention is supported by a housing made of insulating material such as molded plastic, and consists of a mounting block 1 and two similar cover blocks 2 and 3, which blocks are held together by screws 5 and 7, and bolt 8. Screws 6 and 7 fit into threaded inserts 16, 17 (Fig. 4) molded into block 1, with their ends protruding into a round recess 19 having an upper straight portion, as shown in Figs. 4 and 5. Holes 11, 12, 13 may be provided in blocks 1, 2, 3 for the purpose of suitably fastening the switch to a support such as a chassis or switchboard. Ventilating slots 18 may be provided as indicated in Figs. 3 and 4.

Two heat-responsive actuator strips 22, 23, for example consisting of bimetal, have on one side widened ends with holes 25 (Figs. 4 and 5) which are slipped over the protruding ends of inserts 16, 17, recess 19 preventing strips 22, 23 from rotating on the inserts. The strips are held in place by bosses 26, 27 on cover blocks 2, 3 (Fig. 3) which fit into recesses 28 of block 1.

The actuator strips may be provided with heater coils 32 and 33, preferably wound on insulating sleeves 31 of the type shown in Fig. 17.

The ends of the heater wire or wires may be connected to terminal bars 36, 37, 38, 39 which have V-shaped deformations 41 and fit into corresponding recesses 42 of block 1 wherein they are positively confined when the mounting blocks 55 are screwed together.

Molded into mounting block 1 are two pivot bars 51, 52 whose protruding ends are provided with pivot notches 53, 54 (Figs. 1 and 2).

A bar or rod 55 connects the free ends of actuator strips 22 and 23, the ends of bar 55 being secured within holes 24, for example by means of peripheral recesses 57 on adjustment sleeves 56 screwed to the threaded ends of bar 55 and accessible through openings 58 of blocks 2 and 3, which openings may be closed by screws 59. Recesses 57 provide pivots permitting free movement of the actuators while determining the distance and effect thereof, as will be described in detail below.

A conventional switch spring 60 (Figs. 4 and 5) has two compression branches 61, 62 and therebetween a tension branch 63. The common portion 64 carries a contact point 65. The end of the tension branch 63 is shaped to engage an intermediate point of connecting bar 55, for example by means of a simple perforation 66, a button hole 67 or a hook 68 (Figs. 13 and 19) contacting a central peripheral groove 69 of bar 55. The ends 70, 71 of the compression branches 61, 62 rest in pivot notches 53, 54 of supports 51 and 52. Tension branch 63 is shorter than compression branches 61, 62, so that the latter will slightly buckle when opening 60 engages groove 69 and the tension branches rest in notches 53, 54, provided of course that, as shown in the present instance, the notches are arranged at the approximate height of the connector groove 69.

In the figures, the contact 65 is shown throughout in central position between faces 82 and 83; it should be understood that this position has been selected for the sake of convenient presentation only and that the movable contact will always rest on one or the other of these faces.

The contact point 65 cooperates with contact faces 82, 83 which are part of L-shaped contact bars 84, 85 molded into cover blocks 2 and 3 which have recesses 86, 87 forming together a chamber confining the contact point 65. The contact bars 84, 85 protrude from blocks 2 and 3 with terminal ends 88 and 89 which, in order to provide proper spacing, may be staggered as indicated in Fig. 1. The terminal for the double throw switch spring 60, making contact either at 82 or 83, may be at 89, the circuit leading from contact point 65 through branch 63, bar 55, actuator 22 or 23, insert 16 or 17 to screws 6 and 7, either of which may be used as a terminal. It will be understood that one contact face may be replaced by insulation if it is desired to provide a single throw switch.

The above-described embodiment is especially well adaptable for differential actuation when both actuators are provided with heaters as shown in these Figs. 1 to 6, or for use with only one heater on a controlling actuator while the other actuator compensates for ambient temperature within the switch.

If it is desired to apply to one actuator the temperature of the general environment rather than that of the switch structure, an embodiment may be preferable which is similar to that shown in Figs. 7 to 13 which will now be described.

In the embodiment according to Figs. 7 to 13, a mounting block 101 carries inserts 116, 117 holding actuators 122, 123 and connecting to terminal 130 in a manner similar to that described with reference to Figs. 1 to 6. The single heater coil 132 is connected to the single pair of heater terminals 135, 137. The mounting block 101 is extended upwardly beyond spring 130 and carries, moulded

thereinto, a contact bar 189 whose face 183 cooperates with contact point 165 within chamber 186, 187. The contact face 182 of the second bar 188 is moulded into a cover block 102 which is fastened to block 101 by means of screws 106, and bolt 108. Pivot supports 151, 152 with notches 153, 154 are again moulded into block 101, and the arrangement of actuators 122, 123, screws 106, 107, connecting bar 155, and switch spring 160 with branches 161, 162, 163 is similar to that described with reference to Figs. 1 to 6.

The connector 155 reaches actuator 123 through an opening 120 which, if desirable, may be lined with heat-insulating material. Ventilation openings 118 may be provided, as shown in Figs. 7 and 9.

The bare actuator 123 may be protected by a slotted cover plate 104 having a boss 127 fitting into the corresponding recess 142 of block 101 and holding actuator 123 by means of screw 107; a top flange 110 fits a corresponding groove 113 of block 101. Holes 111, 112 may be provided for fastening the switch to a support.

If it is desired to apply the temperatures prevailing at two separate points by means of two bare actuator strips and to render the operation of the switch dependent upon the relation of these temperatures, an arrangement according to Figs. 14 to 17 may be used to advantage. In these figures, the mounting block 201 is provided with a flange 205 by means of which it can be fastened to a wall 200 separating the spaces at different temperatures.

The block 201, similar to block 101 shown in Figs. 7 to 13, has moulded-in inserts 216 and 217 holding the actuator strips 222 and 223 and notched pivot bars 251, 252. Connecting bar 255 together with bars 251, 252 hold the switch spring 260 in the above-described manner. Insert 217 may be contained in a boss 218 of block 201 which protrudes through an opening in wall 200 and carries, fastened thereto by screw 207, a slotted cover plate 203. A second slotted cover plate 202, fastened to block 201 by screw 206 and bolt 208, carries contact bar 288 moulded thereinto, corresponding to a contact bar 289 similarly fastened to block 201. The contact point 265 is arranged between contact faces 282 and 283, as above described. In order better to separate the medium surrounding actuator 223 from that surrounding actuator 222, a heat-insulating bushing 250 may be provided for leading bar 255 through wall 200.

As shown in Fig. 19, the tension branch 263 of switch spring 260 may be pivoted in groove 291 of an adjustment nut 300 threaded to the connector 255, between sleeves 256 with grooves 292, 293 for actuators 222 and 223. In this manner it becomes possible to adjust the relative positions of actuators and switch spring very accurately in order to ascertain proper cooperation of the actuators in moving the switch spring. Means rendering these adjustment sleeves easily accessible may be provided, as indicated by way of example at 259.

It will now be apparent that the inner faces of recesses 19, as shown in Figs. 1 to 6, permanently and accurately define the distance of actuators 22, 23 and that the construction as a whole provides rigid cantilever-like mounting of the actuators. This manner of mounting permits the use of connectors 56 having fixed pivot points whose distance can be predetermined in relation to the actuator distance; it also permits, if desired, the accurate and permanent adjustment of the entire

switch assembly by means of the screws shown in Fig. 19 or similar arrangements. Adjustment of the central pivot at 300 permits change of contact between faces 282 and 283.

It will further be understood that the current conducting connection to the movable contact 65 must not necessarily lead through an actuator but that it may be preferable to connect this contact directly with a conveniently placed terminal, for example through a flexible cord.

The above-described devices operate as follows.

The pivot points 291, 292, 293, 253, 254 of switch 222, 223, 260 (Fig. 19) are so adjusted, either by suitable initial dimensioning or adjustment with the aid of sleeves 256 or nut 300, that contact point 265 assumes under normal conditions the desired position either on contact face 282 or on face 283.

The actuators are so dimensioned and mounted that they provide the desired switch response. Referring for example to Figs. 1 to 5, if the actuators are mounted to deflect inwardly with rising temperature, if their rate of deflection is the same and their heater elements similar, the switch will remain in normal position so long as the currents in the respective coils are the same, in which case the equal tendencies to deflect in opposite directions cancel each other. If, however, one actuator deflection, due to the corresponding heating effect, outweighs the other, the switch will be operated. Assuming for example that point 65 rests normally on contact face 82 and that the actuators deflect inwardly with rising temperature, the contact point 65 will rapidly move from face 82 to face 83 when heater 33 becomes so much warmer than heater 32 that the deflection of actuator 23 towards the left outweighs that of actuator 22 towards the right. Bar 55 will then move towards the left, thereby causing the lines of stress of the switch spring branches to move through a limiting relative position, with the directions of the forces acting on the pivots of the branches of the switch spring passing each other, and point 65 to move rapidly towards the right, connecting terminal 90 with terminal 89 instead of 88. At the same time, any ambient temperature effect is inherently excluded so long as the actuators are not deliberately kept separated as for example in the embodiments of Figs. 14 and 15. It will be evident that any change in ambient temperature will affect both actuators equal'y but in opposite direction, the two virtual deflections cancelling each other. Upon reversal of the temperature relation of the two actuators, the switch will move back into initial position.

If only one heater element is used, as in the embodiment according to Figs. 7 to 13, the second actuator merely provides compensation for ambient temperature changes, rendering the effect of the actuating heater 132 independent of the ambient temperature so that it can be safely relied upon to operate the switch when its heating current attains a definitely determinable value.

In embodiments where the two actuators are not affected by the same ambient temperature conditions, as for example in that shown in Figs. 14 and 15, switches according to the invention can be operated responsive to an absolute difference of two temperature conditions. These temperatures may either be ambient ones or, if one or both actuators are provided with heating coils, the algebraic sum of ambient and superimposed control temperatures will be effective in operating the switch.

It should be understood that the present dis-

closure is for the purpose of illustration only and that this invention includes all modifications and equivalents which fall within the scope of the appended claims.

I claim:

5. 1. A switch of the type having an operating member which is adapted to move with a member connecting the movable ends of two actuator strips having mounting means at their other ends, said switch comprising a mounting block adapted to receive said mounting means of said strips on opposite sides of said block, said mounting block having a wall portion extending cross-wise of and having an opening for said connecting member, a cover block adapted to form with said mounting block an enclosure for said operating member and one of said actuator strips, and means for fastening said cover block to said mounting block.
10. 2. A switch of the type having an operating member which is adapted to move with a member connecting the movable ends of two actuator strips, said switch comprising actuator strips having perforations at the ends opposite to their moving ends, a mounting block having a threaded insert extending beyond the inner face of a depression in said block said insert and said depression substantially fitting one of said perforated ends, cover means fitting said depression, and means for fastening said end in said depression between said block and said cover means.
15. 3. A switch of the type having an operating member which is adapted to move with a member connecting the movable ends of two actuator strips having mounting means at their other ends, said switch comprising a mounting block having a recess formed to fit said mounting means and a groove adjacent said recess, a conductor bar fitting said groove, cover means fitting said mounting means on said recess and said bar in said groove, and means for fastening said mounting means and said bar between said block and said cover means.
20. 4. A switch of the type having a snap switch unit with a tension spring member and a compression spring member joined at a contact portion, one member being supported at fixed pivots and the other member being held at a pivot which is adapted to move with a connector between the movable ends of two actuator strips which extend substantially in the direction of the lines of stress of said members, and which have mounting means at their other ends, said contact portion moving rapidly when the directions of stress of said members pass a limiting relative position due to relative movement of said pivots; said switch comprising a mounting block adapted to receive said mounting means of said strips in positions substantially parallel to said directions, and having means constituting said fixed pivots; a cover block extending alongside said spring members and substantially enclosing one of said strips, and carrying a contact member opposite said contact portion; and means for fastening said cover block to said mounting block.
25. 5. A switch of the type having a snap switch unit with a tension spring member and a compression spring member joined at a contact portion, one member being supported at fixed pivots and the other member being held at a pivot which is adapted to move with a connector between the movable ends of two actuator strips which extend substantially in the direction of the lines of stress of said members, and which have mounting means at their other ends, said contact portion

moving rapidly when the directions of stress of said members pass a limiting relative position due to relative movement of said pivots; said switch comprising a mounting block adapted to receive said mounting means of said strips on opposite sides of said block in fixed positions substantially parallel to said directions, a mounting block having means constituting said fixed pivots; a cover block extending alongside said spring members and substantially enclosing one of said strips, and carrying a contact member opposite said contact portion; means for fastening said cover block to said mounting block; and means associated with said connector for adjusting the distances of said moving pivot and of said movable ends. **15**
